REVERSIBLE RATCHET MECHANISM

Filed Aug. 28, 1947

UNITED STATES PATENT OFFICE

2,505,678

REVERSIBLE RATCHET MECHANISM

Francis R. Kull, Rockledge, Pa., assignor to
 Standard Pressed Steel Co., Jenkintown, Pa., a
 corporation of Pennsylvania

Application August 28, 1947, Serial No. 771,065

2 Claims. (Cl. 192—43.1)

1

This invention relates to ratcheting drive elements and particularly to a ratchet for hand tools such as mechanics' wrenches.

Ratcheting drives for wrenches in current use are unsatisfactory because, if sufficiently rugged to withstand ordinary working forces, they are constructed of such a size as to prevent their use in locations where there is a minimum of working clearance for the wrench and its related parts. Furthermore, the construction of such devices renders them unsatisfactory because slippage frequently occurs and, in many types, the reversing mechanism soon becomes inoperative or is not adapted for quick manipulation. Frequently, in order to obtain sufficient strength, it has been necessary to incorporate the ratcheting device in the wrench handle itself, with the concurrent disadvantage that the handle is needlessly enlarged and expensive.

An object, therefore, of my invention is to provide a cheap but rugged reversible ratcheting drive for a socket wrench in which the ratcheting element has an outside diameter approximately the diameter of the socket employed with the wrench.

A further object of the invention is to provide a reversible pawl for a ratcheting wrench drive which is under compression during the application of driving torque.

A further object is to provide a pointed toggle action reversible pawl for a ratcheting socket wrench drive element.

A further object of the invention is to provide a transverse shaft for reversing the pawl in a ratcheting wrench element operable by a crown on the side of the element.

A further object of the invention is to provide a spring loaded pawl having a pair of 60° teeth tapered with respect to each other and adapted to be selectively engaged in the notches of a ratcheting wrench drive member by means of a manually operated crown on the side of the member.

A further object is to provide a locking pawl for a ratcheting wrench element which transmits driving torque through compression of the pawl against one side of an extended slot in the wrench element.

The invention resides further in certain structural details contributing to the aforesaid primary ends, said details being hereinafter described and illustrated in the attached drawings, in which:

Fig. 1 is a side elevation of a ratcheting drive element constructed in accordance with the invention.

2

Fig. 2 is a sectional view of the structure of Fig. 1.

Fig. 3 is a sectional view taken along lines 3—3 of Fig. 1.

Fig. 4 is a perspective view of the pawl and the pawl housing with the ratcheting member and casing removed.

Fig. 5 is an enlarged detail of the pawl and the ratcheting member diagrammatically illustrating the composition of turning forces.

Referring now more particularly to the drawings, a ratcheting drive element constructed in accordance with the invention has a pawl housing 10 in which is milled a transverse slot 11, the sides of which form a pair of ears 12 and 13 having outwardly curved sides. Ear 12 is substantially thicker than ear 13 due to the fact that slot 11 is offset from the center line of the housing 10 (Fig. 1) and in addition extends beyond the end of ear 13 to form an abutment 14 for pawl 15 and also a guiding shoulder 16 at the end of ear 12. Housing 10 extends oppositely to form a hexagonal shank 17 in which are located notches 18 for reception of spring pressed retaining elements in the socket of the wrench or other member through which turning force is applied to the hexagonal shank. The housing is centrally drilled at 19 to accommodate helical spring 20 and steel ball 21, which cooperates with the lower pointed end 22 of pawl 15 to urge the pawl to pivot on shaft 23 which is in turn supported in ears 12 and 13.

Pawl 15 has a somewhat diamond shaped configuration, the lower portion of which terminates in a 90° point providing a toggle action with steel ball 21, whereas the upper portion of the pawl carries two outwardly facing 60° teeth 24 and 25 which are cut at an angle with each other. The upper portion of the pawl is milled away on a line parallel to the face of teeth 24 and 25 to form a reinforcing foot or compression member 26 which abuts the flat face of ear 12 and extension 14 in all positions of pawl 15. Hole 27 in the pawl has a raised flat 28 which is in alignment with flat 29 on shaft 23, thereby locking the pawl to the shaft and thus enabling the pawl to be pivoted by rotating the shaft.

Ratcheting member 30 has a circular hollow head 31 of the same outside diameter as housing 10 and is designed to abut the ends of ears 12 and 13. Head 31 of the ratcheting member carries on its inside periphery twelve broached teeth 32 between which are formed twelve notches 33 having sides set at an angle of 60° with each other (Fig. 5). Ratcheting member 30 likewise extends

in the opposite direction to form a hollow shank 34 having a hexagonal internal broach adapted to receive a socketed tool element or other driven element which engages the work pieces to which the turning torque is to be applied.

Circular casing 35 encloses ratcheting member 30 and housing 10 and serves to maintain these members in proper alignment with respect to each other. This is accomplished by the fit of annular lip 36 on casing 35 adapted to rotate on shoulder 37 of member 30, and rigid attachment between the opposite edge of casing 35, which is peened to the main body portion of housing 10. Slight turning clearance is permitted between member 30 and casing 35, but this clearance is not great enough to permit noticeable end play or misalignment of members 10 and 30. Shaft 23 extends through casing 35 and is permanently secured therein, after assembly of the ratchet elements, by means of washer 38 over which the shaft 23 may be peened. Crown 39 is secured to the opposite end of the shaft and fits in a circularly milled recess 40 on the upper face of casing 35.

The notches 33 in head 31 formed between teeth 32 have sides set at 60° angles with each other. This construction insures that, regardless of the diameter of the head 31 of member 30, one side of two notches will at some time be parallel with the sides of slot 11. Teeth 32' and 32'' in Fig. 3 have one side parallel and in line with the inner face of ear 13 and the position of these two teeth determines the location of slot 11 in housing 10. It will thus be apparent that when pawl 15 is pivoted in slot 11 on shaft 23 as an axis, either tooth 24 or tooth 25 will engage in the notch of head 31 which is opposite the maximum pivoting position of the pawl. Turning the crown 39 against the action of spring 20 serves to snap pawl 15 into opposite notches in member 30, depending upon the direction of relative rotation between members 30 and 10 which may be desired. With this construction it is possible to permit rotation in either direction merely by holding pawl 15 in a substantially vertical position so that neither tooth 24 nor tooth 25 engages member 30 at all.

Referring now to Figs. 2 and 3, it will be evident that rotation of member 10 in a clockwise direction tends to lock pawl 15 with respect to member 30 and therefore driving force is transmitted from member 10 to member 30. Counter-clockwise rotation of member 10, however, causes pawl 15 to pivot on shaft 23, thereby permitting a ratcheting action in this direction. The opposite ratcheting effect is readily achieved by reversing the position of the pawl 15 with respect to member 30 so that the pawl will bear against face 32'' instead of face 32'. In this position counter-clockwise turning of member 10 transmits torque to member 30, whereas clockwise turning of member 10 produces the ratcheting action. Spring 20, acting through ball 21, continues to urge the tooth 24 or 25 as the case may be, into successive notches of member 30 during the ratcheting action.

Fig. 5 illustrates in greater detail the peculiarly good ratcheting and locking results which are obtained primarily by means of the shape and location of the notches 33 in member 30, as well as the teeth 24 and 25 in pawl 15. Clockwise rotation of member 10 in Fig. 5 produces a turning force upon the member 30 which may, for the purposes of our illustration, be considered to be concentrated at point O and in the direction OS,

a line drawn normal to the radius of head 31 at point O. The pawl 15, in this position, is permitted to move on its pivot only in the direction OQ in Fig. 5, and it will be apparent that there is no component of force S reacting upon the pawl in the direction OQ. However, there is a component OP reacting on the pawl in the opposite direction, and another component reacting in the direction OR. These two reactions of the turning force S combine to lock pawl 15 more tightly in member 30. Furthermore, the reaction forces upon the pawl are not imposed upon the shaft 23 but directly upon the ear 12 and extension 14. The greater the turning force applied to member 10, the greater will be the locking action of tooth 25 with respect to member 30.

Counter-clockwise rotation of member 10, however, produces an entirely opposite effect, as diagrammatically illustrated in Fig. 5. In this case the sum of the turning forces on the member 30 may be represented as concentrated at point B and acting in a direction BH at right angles to a radius of the head 31 at point B. Force H now has a component C acting in the direction BC which by reaction upon the tooth 25 tends to disengage the tooth from notch 33, thereby causing pawl 15 to pivot on shaft 23.

The off-center location of slot 11 not only provides for parallel engagement of teeth 24 and 25 with suitable notches in head 31, but also permits strengthening of ear 12 in order to better withstand the forces transmitted through pawl 15 in the manner described above.

The ratchet drive is cheap to manufacture, and of extremely rugged construction. It is adapted to be used not only for hand tools such as socket wrenches, but may be applied to any driving mechanism in which one-way driving torque is required.

While certain novel features of the invention are disclosed herein in considerable detail with respect to certain particular forms of the invention, it is not intended that the invention be limited to such details since many changes and modifications may well be made without departure from the spirit of the invention in its broadest aspects.

I claim:

1. A ratcheting device comprising a pawl housing having a pair of ears forming side walls for the housing, one of said ears being thicker than the other ear, a pawl pivotally supported between said walls, a hollow rotating member adapted to abut the ends of said ears, a guide on one of said ears extending into the hollow portion of the ratcheting member to provide alignment for said member, a plurality of notches around the internal portion of the ratcheting member, and a tooth on one end of the pawl for engaging one of said notches, the shape of the notches and tooth being such that turning force applied through the pawl to the ratcheting member in one direction resolves into two components, one of which forces the pawl into tighter engagement with the notches, and the other of which compresses the pawl against the larger ear and guide to transmit the turning force to the housing.

2. A ratcheting device comprising a pawl housing having a pair of ears forming side walls for the housing, one of said ears being thicker than the other ear, a pawl pivotally supported between said walls, a hollow rotating member adapted to abut the ends of said ears, a guide on one of said ears extending into the hollow portion of the ratcheting member to provide alignment for said

member, twelve 60° notches around the internal portion of the ratcheting member, and a 60° tooth on one end of the pawl for engaging one of said notches, the shape of the notches and tooth being such that turning force applied through the pawl to the ratcheting member in one direction resolves into two components, one of which forces the pawl into tighter engagement with the notches, and the other of which compresses the pawl against the larger ear and guide to transmit the turning force to the housing. 10
